(57) **CLAIM**

The ornamental design for a dental implant, as shown and described.

DESCRIPTION

FIG. 1 is a perspective view of a dental implant showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a cross-sectional view thereof taken along line 8—8 in FIG. 7.

The broken lines shown in the drawings are included for the purpose of illustrating environmental structure and form no part of the claimed design.
